UNITED STATES PATENT OFFICE.

GLENN H. CURTISS, OF BUFFALO, NEW YORK, ASSIGNOR TO THE CURTISS MOTOR COMPANY, OF HAMMONDSPORT, NEW YORK, A CORPORATION OF NEW YORK.

FLYING-MACHINE.

1,228,382.

Specification of Letters Patent. Patented May 29, 1917.

Application filed July 14, 1915. Serial No. 39,836.

To all whom it may concern:

Be it known that I, GLENN H. CURTISS, a citizen of the United States, residing at Buffalo, in the county of Erie and State of New York, have invented certain new and useful Improvements in Flying-Machines, of which the following is a specification.

My invention relates to aeroplanes of the heavier-than-air type and has particularly to do with those types of aeroplanes intended to travel at relatively high speeds. For high speed work it is essential that the machine be both freed of head resistant surfaces or formations and be well balanced. The first essential makes directly for increase in rate of travel, while the second indirectly produces the same result, in that the machine is more responsive to its controls and its directional changes are carried out with more efficiency and at a higher rate of speed. My invention is possessed of these speed characteristics to a marked degree and yet its structural form is such that the body of the craft is also possessed of the highest strength. Thus a craft built according to my invention travels at the very maximum possible speed with the very highest factor of safety.

A machine in which my invention is embodied is delineated in the accompanying drawings.

Figure 1 is a side elevation.

Fig. 2 is a top plan view.

Fig. 3 is a front elevation.

Fig. 4 is an enlarged side elevation of the 35 wheeled part of the landing gear.

Fig. 5 is a perspective view of an equalizing member of this gear from the inside.

Fig. 6 is a transverse section of the same.

Figs. 7 and 8 are side and front elevations 40 respectively of my invention as embodied in the flying boat.

Fig. 9 is a cross section of the bulwark of the boat showing the termination of the planking short of the top and the light covering 45 of the top of the boat.

Fig. 10 is a diagrammatic front elevation of the modified form of the landing gear.

Reference to the various parts of the machine is by means of the numerals designating 50 them upon the drawings.

(10) The main supporting surfaces of the craft, of which as shown, there are two, constituting, together, a biplane cell. Any suit-

able number of supporting surfaces, one or more, and arranged with respect to each other in suitable manner, may be used.

(11) Driving motors for the machine. These driving motors are two in number in the embodiment shown, though there may be used one or more. In any case they are symmetrically disposed with respect to the vertical line passing through the center of lift of the main supporting surfaces or of the craft as a whole. This center of lift lies on the longitudinal axis of the machine (indicated by dotted lines Fig. 2) and it will be seen that the motors 11 illustrated lie substantially parallel to and equidistant from this axis. They are supported in elevated positions midway between the supporting surfaces 10. They are of the tractor type, having propellers on their front ends as indicated and arranged to draw the machine forward through the air.

(12) A nacelle connected with the main supporting surfaces, in this instance below the lowermost one of them. It is of streamline form, approximately symmetrically disposed with respect to a vertical line passing through the center of lift.

(13) The approximate location of the vertical line passing through the center of lift.

(14, 15) Seats for passengers located in the nacelle. The seats 14 are located in front of the tractor ends of the motors 11, while 85 the seat 15 is located aft thereof. These seats, of which there may be one or more, in each case, are located also approximately symmetrically with respect to the center of lift line 13. 15 is the pilot's seat.

(16) The fuel supply tank located in the body of the nacelle intermediate the seats 14, 15.

(17) An ammunition locker located intermediate the fuel supply tank 16 and the front seats 14. The contents of the supply tank and the locker 17 are exhaustible and these are located in proximity and approximately symmetrically with respect to the center of lift line 13 whereby as the contents are exhausted there is no disturbance of the balance of the machine.

(18) Radiators for the motors located at their front ends.

(19) Streamline housings for the motors 105 tapering from the point of greatest cross sec-

tion at the radiators 18 to a point of minimum cross section aft of the motors.

(20) The engine beds.

5 (21) A pair of spars connected one to each engine bed and extending rearwardly in tapering form from ends of the engine beds 20 to which they are rigidly secured and in continuation of the streamline form of the housings 20 over the motors.

10 (22) A third spar similar to the spars of the pair 21 firmly secured to the rear end of the nacelle structure and extending rearwardly in continuation of the streamline form of the nacelle 12 and in a vertical plane 15 midway between the spars of the pair 21, but somewhat below the same.

(23) A horizontal stabilizer supported in an approximately horizontal position by the outer ends of the pair 21.

20 (24) A transverse mainbeam of the stabilizer 23 to which the outer ends of the pair of spars 21 are connected.

(25) A vertical stabilizing surface supported between the after end of the spar 22 25 and the horizontal stabilizer 23.

(26) A vertical strut between spar 22 and the horizontal stabilizer 23.

(27) A transverse beam in the body of the stabilizer itself, to which strut 26 is directly 30 connected. Outer ends of beam 27 are connected to the respective spars of the pair 21.

(28) A vertically extending rudder post between the extremity of spar 22 and the horizontal stabilizer beam 24.

35 (29) A vertical rear rudder hinged to rudder post 28.

(30) A pair of elevator flaps one hinged to the horizontal stabilizer 23 on each side of rudder 29.

40 (31) Suitable cross wiring or bracing between spar 22 and the spars of pair 21 which makes of the whole a rigid rearwardly extending fuselage structure supporting the control surfaces 23, 25, 29, and 30 at its 45 outer end.

(32) Axle members extending laterally in tandem pairs from the sides of the nacelle 12. These axle members are hinged at their inner ends to the nacelle whereby their outer 50 ends may partake of movement in vertical planes.

(33) Tandem or following wheels mounted in pairs on the outer ends of the axles.

55 (34) An equalizing member interconnecting the tandem wheels. The particular form of this member is immaterial. As shown it is a flexible, laminated bow spring whereby the equalizing connection becomes also a yielding connection. The top lamination of this spring has two arches near its center.

(35) A pillar support depending from the supporting surface structure above the wheels and pivotally connecting with the 60 equalizing member 34 at a point interme-

diate its ends. The lower end of pillar 35 is convexed and bears against the arches of member 34 above mentioned. This member transmits the thrust of the landing gear directly to the main structure of the machine.

70 (36) A rearwardly extending brace to the end of the pillar support 35. Preferably the pillar support 35 is joined at its upper end to the front main beam of the supporting surface, while the upper end of the brace 36 is joined to the rear beam thereof in each case. This structure is duplicated on opposite sides of the machine.

75 (37) Strong cross wiring between the pillar support 35 and the sides of the nacelle structure. It will be observed that there is a pair of following wheels directly beneath each driving motor 11.

80 (38) Driving motor supports in the same plane as the driving motors and the following wheels of the landing gear.

85 In operation as the machine is started from the ground into the air or alights upon the ground from the air the following wheels take up directly the impact of landing, the heavy masses of the driving motors being directly imposed upon them and the body structure being midway between the pairs on opposite sides of the machine. The equalizing connections 34 between the 90 wheels equalize the loads upon the individual wheels of the pairs, each wheel rising up and down with its axle and the pairs having oscillatory movement about the points of rocking or pivotal connection with 95 the posts 35 as they pass over small or large obstructions. By virtue of this connection the machine is of an extremely easy riding nature on land, but of far more value than that, is the freedom of shock to vital parts 100 and the extreme sturdiness of the gear itself. Because the wheels are following or tandem they present a minimum head resistance per pair.

105 When the machine is in the air, because 110 of the streamline nature of the motor housings and nacelle and the longitudinal members of the fuselage structure in direct continuation thereof and approximately in longitudinal parallelism, there is a very minimum 115 of drag. There are no projecting head resistant surfaces of an unuseful nature. Extreme speed is attainable under these conditions and yet the spars are so grouped (in their triangular arrangement) and capable 120 of being so trussed together (as indicated by the wires or braces 37) that the highest factor of safety desired may be attained.

125 By the seat arrangement herein disclosed an unobstructed observation and gun fire range in both a vertical and a horizontal plane may be had from the forward seat through an arc of approximately one hundred and eighty (180°) degrees. The range from the rear seat, although somewhat obstructed in 130

a horizontal plane is approximately equal to that of the forward seat since said seats are located respectively in advance of and aft of the total supporting surface area of the machine.

5 The embodiment of Figs. 7 and 8 is in the form of a flying boat.

(39) is the hull of the flying boat which is substituted for the nacelle 12 and the associated running gear of the form of Figs. 1, 2 and 3. This boat is of an elongated streamline form and its body is inclosed. In fact the frame work of the hull proper terminates at the longitudinal dotted line extending through the lower plane 10, see Fig. 9, and the top is covered over with a covering of extremely light material such as aluminum, canvas or veneer planking. The tail of the boat takes the place of the spar 22 of the form of Figs. 1, 2 and 3 and is combined with the spars 21 to form the fuselage structure supporting the control devices 23 to 30.

(40 and 41) Seats for passengers located respectively fore and aft of the main supporting surfaces 10, and approximately in the same relation to the remaining elements of the machine as seats 14 and 15. 41 is the pilot's seat.

30 (42) Ex crescent planing fins in extension of the bottom of the boat and constituting additional planing area.

(43) Bracing members between the lowermost supporting surface and these fins whereby they are braced directly to the supporting surfaces.

This flying boat possesses the same speed characteristics as the land machine hereinbefore described. The slim, streamlined body of the boat 39 takes the place of the nacelle 12 and spar 22 most effectively. Strength, efficiency of control and speed are attained to an equal degree.

45 Fig. 10 discloses a modified form of landing gear for the land type of machine of Figs. 1 to 3. It differs from the form of Figs. 1 to 3 principally in that the axles 32 are carried to a point near the central plane of the nacelle and pivoted to an outward extension therefrom instead of to the bottom edges. The axles are then straight instead of bent as are the axles of the form of Figs. 1 to 3.

I claim—

55 1. In an aeroplane, main supporting surfaces, twin driving motors, a nacelle for seating the passengers, and a fuselage supporting the rear controls and comprising three longitudinal members trussed together, one extending aft from each motor, the other extending aft from the rear end of the nacelle.

60 2. In an aeroplane, main supporting surfaces, driving motors, a nacelle structure for carrying passengers, and a fuselage car-

rying controls and comprising a plurality of longitudinal members extending one, at least, from each of the motors and the nacelle.

3. In an aeroplane, main supporting surfaces, a driving motor, a motor support, a nacelle, and a fuselage structure including longitudinal members extended rearwardly as actual prolongations respectively of the motor support and of the nacelle, said members in each instance terminating forwardly in the vicinity of the aft end of the structure which they prolong. 75

4. In an aeroplane, main supporting surfaces, a driving motor mounted intermediate the supporting surfaces, motor supports interconnecting the respective supporting surfaces, engine bed beams interconnecting corresponding motor supports, rear controls, and a longitudinal member extending rearwardly in prolongation of the engine bed beams to carry said rear controls. 80

5. In an aeroplane, a nacelle structure, twin driving motors mounted without, in a horizontal plane above and respectively at 90 opposite sides of the nacelle, rear controls, and a longitudinal member extending rearwardly in prolongation of each motor and the nacelle, said members collectively constituting a fuselage structure for supporting 95 the rear controls.

6. In an aeroplane, main supporting surfaces, a nacelle structure, a seat located in the nacelle forwardly of the total supporting surface area to provide an unobstructed 100 observation range, and an unobstructed gun fire arc of at least one hundred and eighty (180°) degrees in both a vertical and horizontal plane, a seat located in said nacelle aft of said total supporting surface area, 105 and a propelling means for the craft.

7. In an aeroplane, main supporting surfaces, a nacelle structure having an overall length sufficient to extend well beyond the total supporting surface area both fore and aft, a passenger's seat located in the forwardly extended portion of the nacelle, a pilot's seat located in the aft extended portion of the nacelle, and a propelling means 110 for the craft. 115

8. In an aeroplane, a nacelle structure, a seat located in the nacelle adjacent its forward end, supporting surfaces arranged to extend transversely across the nacelle aft of said seat, a tractor propeller located intermediate said seat and said surfaces, a power plant, rear controls, and a longitudinal beam member extended aft from the rear of said nacelle to support said rear controls. 120

9. In an aeroplane, main supporting surfaces, a nacelle structure having an overall length sufficient to extend well beyond said supporting surfaces both fore and aft, a seat located in each of the extended portions of the nacelle, rear controls, a longitudinal 125 130 135

beam member extended aft from the rear end of the nacelle to support said rear controls, and a propelling means for the craft.

10. In an aeroplane, main supporting surfaces, a nacelle, a passenger's seat located in the nacelle forwardly of the supporting surfaces to provide for both an unobstructed observation range and for an unobstructed gun fire arc of over 160 degrees in a horizontal plane, a pilot's seat located in the nacelle aft of the supporting surfaces, and a propelling means for the machine located aft of the passenger's seat and forwardly of the pilot's seat for operation in the horizontal plane above the nacelle.

11. In an aeroplane, in combination, main supporting surfaces, a tractor driving means, a seat for a passenger in front of the tractor end of said driving means, a seat for a passenger aft of the front end of said driving means, the location of said seats and driving means being such that the center of mass thereof lies in proximity to a vertical line passing through the center of pressure of said supporting surfaces.

12. In an aeroplane, main supporting surfaces, a plural number of flight resisting masses arranged one above the other to support respectively the driving motor and the flying crew, an empennage, and longitudinal beam members extending aft respectively from at least two of said masses to collectively constitute a fuselage and support for the empennage.

13. In an aeroplane, main supporting surfaces, driving motors therefor, spars extending rearwardly from said driving motors, a body structure containing seats for passengers, and giving a streamline rearward extension, and vertical and horizontal controls supported by the extension of said body structure and said spars in conjunction.

14. In an aircraft, a nacelle, propelling means, a beam extending aft from the rear end of the nacelle, beams extending aft from the propelling means in a horizontal plane above the first mentioned beam, and a connection between the respective beams constituting therewith a fuselage for supporting the empennage of the aircraft.

15. In an aeroplane, main supporting surfaces, twin driving motors mounted one at

each side of the longitudinal axis of the aeroplane, a nacelle, and a fuselage supporting the rear controls and comprising beams extending aft from the respective motors and from the nacelle.

16. In an aeroplane, main supporting surfaces, a nacelle, a driving motor mounted in a horizontal plane above the nacelle, and a fuselage for supporting the empennage of the aeroplane comprising connected beams extending aft from the nacelle and from the motor.

17. In an aeroplane, main supporting surfaces, driving motors mounted one at each side of the longitudinal axis of the machine, a nacelle, and a fuselage carrying controls and including beams extending respectively aft in prolongation of each of the motors and the nacelle.

18. In an aeroplane, main supporting surfaces, a nacelle of a construction tapering aft and of a length to extend forwardly beyond the leading edge of said supporting surfaces and aft beyond the trailing edge thereof, propelling means mounted on opposite sides of the longitudinal axis of the machine and to operate in paths overlying the nacelle, and seats located in the nacelle respectively fore and aft the supporting surfaces and fore and aft the propelling means.

19. In an aeroplane, main supporting surfaces, horizontally disposed principal flight resisting masses arranged one above the other to support respectively the motor and the flying crew, rear controls, and means continuing said masses rearwardly in the form of beams to provide in effect a fuselage structure for the support of said rear controls, the fuselage structure at its forward end terminating aft of the vertical plane of the leading edge of said supporting surfaces.

20. In an aeroplane, main supporting surfaces, horizontally disposed principal flight resisting masses arranged one above the other to support respectively the motor and the flying crew, rear controls, and means continuing said masses rearwardly to provide in effect and in a vertical plane a dual support for said rear controls.

In testimony whereof I affix my signature.

GLENN H. CURTISS.
